UNITED STATES PATENT OFFICE.

ALBERT RUEHE, OF NEW YORK, N. Y.

FAUCET.

SPECIFICATION forming part of Letters Patent No. 251,953, dated January 3, 1882.

Application filed June 13, 1881. (Model.)

To all whom it may concern:

Be it known that I, ALBERT RUEHE, of the city, county, and State of New York, have invented certain useful Improvements in Faucets, of which the following is a specification.

The object of my invention is to provide a new and improved faucet which can be fastened in the barrel without striking or hammering.

10 The invention consists in a faucet provided with an upright arm near its inner end, which arm is passed under a catch on the upper end of a plate fastened to the head of a barrel, and provided with a bushing fitting in the bung-hole, upon which the outer end of the faucet is depressed, whereby the inner end forces the cork into the barrel, upon which a handled ring mounted loosely on the faucet and provided with a beveled cam is turned, whereby

20 the annular shoulder of the faucet, provided with a packing-ring, is forced against the plate on the barrel-head, the beveled cam sliding on a projection on the lower end of the plate on the barrel-head.

25 In the accompanying drawings, Figure 1 is a longitudinal sectional elevation of my improved faucet and of the end of the barrel, showing the manner of fastening the faucet. Fig. 2 is a longitudinal sectional elevation of 30 the same, showing the faucet in position. Fig. 3 is a cross-sectional elevation of the faucet. Fig. 4 is an end view of the ring with the beveled cam. Fig. 5 is a front elevation of the plate on the front barrel-head. Fig. 6 is a plan view of the same.

35 Similar letters of reference indicate corresponding parts.

The faucet A is provided near its rear end with an upright slightly-curved rigid arm, B, 40 and with an annular shoulder, C, at the base of this arm. A packing-ring, D, rests against the inner surface of this shoulder C. A ring, E, provided with a handle, F, and a beveled segmental cam, G, is loosely mounted on the 45 faucet A between the shoulder C and a like shoulder, H, to the front of the shoulder C. A plate, J, provided at its upper end with a catch or recessed projection, K, and with a bushing, L, fitting into the stopper-hole or bung-hole 50 M, is attached to the head N of the barrel, which is provided with a beveled recess, O, under this plate. This plate is provided at its lower end with an outward-projecting flange, P, provided at its outer end with a projection, 55 Q, the inner edge of which is beveled. The

bushing L increases in diameter toward the inside of the barrel.

The operation is as follows: The upper end of the arm B is placed under the catch K, the inner end of the faucet resting against the 60 stopper E. The outer end of the faucet is then depressed, causing the inner end of the faucet to press the stopper R into the barrel, the inner end of the faucet passing into the bushing L. The handle F of the ring E is then turned 65 in the direction of the arrow x', causing the beveled surfaces of the cam G and of the projection Q to slide on each other, whereby the shoulder C is pressed firmly against the packing-ring D, which in turn is pressed against 70 the plate J, whereby leaking is prevented. The beveled cam locks the faucet firmly in position.

To remove the faucet the above operations are performed in the inverse order and direction.

The faucet need not be driven into the barrel. The operation is noiseless, and none of the liquid contained in the barrel is lost.

Having thus fully described my invention, 80 I claim as new and desire to secure by Letters Patent—

1. A faucet constructed, substantially as herein shown and described, with an arm, B, and with a cam-ring, E, loosely mounted thereon, 85 in combination with keeper K and projection Q on the head of the barrel, as set forth.

2. The combination, with the faucet A, provided with the arm B, and the cam-ring E, having a handle, F, of the plate J, attached to the 90 barrel, and provided with a beveled projection, Q, at the end of its bottom flange, P, and with a catch, K, at the upper end of the plate.

3. The combination, with the faucet A, of the arm B, the shoulders C and H, the packing-ring D, and of the ring E, loosely mounted thereon, and provided with a beveled cam, G, and a handle, F, substantially as herein shown and described, and for the purpose set forth.

4. The plate J, attached to the head of a barrel, and constructed with a catch, K, at its upper end, a bushing, L, and with a bottom flange, P, with a beveled projection, Q, at its outer edge, in combination with the faucet A, provided with the arm B, and the cam-ring E, substantially as herein shown and described, and for the purpose set forth.

Witnesses: ALBERT RUEHE.
